Application May 15, 1953, Serial No. 355,321

Claims priority, application France May 17, 1952

5 Claims. (Cl. 214—656)

My invention has for its object a mechanical device 15 for loading the waste or excavated material produced in the sinking of vertical mine shafts or pits, the depth of which may reach many hundreds of feet.

It is a well-known fact that nowadays the waste material is loaded by hand into hoistable buckets which are then raised above ground by the hoisting winch. After each clearing of the loose material, all hands and machinery must leave the bottom of the pit to allow firing the explosive charge for loosening a further layer of variable thickness. As concerns the clearance and by reason of the narrowness of the bottom of the pit and of the necessary removal of hands and of machinery before each firing, it is not possible to substitute for the hand-operated loading of the kibbles a mechanical loading as provided by conventional mechanical means, such as mechanical excavating shovels, loading machines, cranes with grab buckets and the like, for any such mechanical equipment would be in line with, and liable to damage by, debris blown upward by the explosion.

My invention has for its object to remove this drawback and to allow using an excavating shovel adapted to be brought during the actual firing out of the reach of the upwardly projected loosened material.

To this end, my invention consists in an arrangement for the mechanical loading of the loose material produced in the boring of vertical pits; according to my invention, I provide an excavating shovel suspended from a service platform by a system of several flexible cables, each whereof may be hauled in or paid out independently of the other cables, while independent but cooperating controlling means are associated with the corresponding cables and their suspension and winding means. The suspension means for these cables define, on the bottom of the pit and in vertical register with said suspension means, a polygonal outline whereby to increase the surface over which the excavating shovel may operate, by cooperative control of the independent control means, to include the entire polygonal area, so as to clear the whole surface of the bottom of the pit, whereby any material taken by the shovel from any point of the bottom may be transferred to any other point of said bottom. By the same suspension means the excavating shovel may be raised substantially into contact with the service platform during the firing of explosive charges, where it is at a safe distance, such that it will not be damaged by flying rocks.

In one specific embodiment of my invention, the cables are controlled by three independent winches so that the lengths unwound by each cable may vary independently of one another.

According to a different embodiment of my invention, the cables may be controlled by a single winch including three independent drums.

According to yet another feature of my invention, the independent cooperating cable-controlling means are provided with a remote control system so that a single man may proceed with the different operations to be executed.

2

My invention covers also suspension means including at least three cables so as to prevent any pendular rocking of the excavating shovel during its lowering, which rocking might be dangerous for any one remaining at the bottom of the pit.

Further objects of my invention consist in: providing the excavating shovel with means such as a cylinder inside which a piston controlled by a fluid moves so as to effect the opening and the closing of the shovel; providing the head of the excavating shovel with safety means cutting out any risk of an accident in case of a failure of the supply of fluid controlling the opening and the closing of the same; providing the independent cooperating cable-controlling means with a remote control system carried by a control station which may be secured to the wall of the pit or suspended from a winch, or located at some other distant point, which arrangement allows a single operator to control the work as a whole.

Further features and advantages of my invention will appear in the reading of the following description, reference being made to accompanying drawings which illustrate diagrammatically various embodiments of my invention, and which are given by way of a mere exemplification and by no means in a limiting sense. In said drawings:

Fig. 1 is a vertical cross-sectional view of a pit the waste material at the bottom of which, loosened previously by the firing of an explosive charge, is ready to be removed; this figure illustrates the conventional removal thereof by hand.

Fig. 2 is a similar view of the same pit the service platform of which carries, suspended therefrom, an arrangement according to my invention.

Fig. 3 is a view similar to Fig. 2 showing the excavating shovel raised into proximity with the lower surface of the service platform after the boring of the blasting holes and before the firing of the explosive charges therein.

Fig. 4 is a diagrammatic plan view of the same pit showing the arrangement of the suspension points for the cables.

Fig. 5 is a diagrammatic plan view of the same pit equipped with a modified arrangement according to my invention, wherein a single winch having three independent drums controls the different cables.

Fig. 6 is a vertical sectional view of a pit from the service platform of which is suspended an arrangement according to my invention, which is a modification of that shown in the preceding figures.

Fig. 7 is a view of the excavating shovel of Fig. 6 in its closed and locked position.

Fig. 8 shows the same excavating shovel in its open position.

Fig. 9 is a detail view at a larger scale showing the safety means provided for said excavating shovel.

When operating in accordance with known or conventional methods as illustrated in Fig. 1, a gang of workmen shown at 2 loads manually the excavated material by shovelling it into the hoistable bucket 3 which, when filled, is hooked onto the cable 4 of the hoisting winch (not shown), which raises it above ground, while the second cable 5 of the hoisting winch unwinds and brings another, empty bucket down for a further removal of material.

A service platform 6 is suspended from a cable 7 wound over a control winch (also not shown) located above ground. The service platform 6 may thus be raised or lowered as desired. It is intended for the placement of the cylindrical concrete wall 8 inside the pit and it may also serve as a service platform to be positioned at any desired height for the planking of the pit or the like operation.

It is apparent that by reason of the use of blasting

charges for the loosening of material at the bottom of the pit, the service platform 6 should be, when not in use, raised at a substantial height above said bottom, where it will not be damaged by flying bits of rock.

When the excavated material 1 has been completely removed, blasting holes 20 are bored, as shown in Fig. 3 and, when the explosive charges are being fired in the blasting holes, the bottom of the pit should be cleared of any hands or machinery.

By reason of the comparatively large amount of excavated material to be removed and of the diameter of the pit, it has been necessary heretofore to resort to a gang of workmen for the loading of the buckets since the use of loading machinery in the nature of fixed installations, yet which must be removed before each firing, and restored thereafter to operating position, is economically impractical.

According to the present invention I provide mechanism whereby, virtually without manual labor, loosened material not only at some one point, but in any part of the area at the bottom of the shaft, can be engaged and lifted, and loaded into a bucket which rests upon the bottom, without interfering with the lowering of empty buckets or the raising of full buckets. The use of such mechanism eliminates substantially all of the back-breaking manual labor, not only in the loading but also in the positioning of the shovel, and both reduces the number of workmen required and speeds up the removal of loosened material. At the same time, in accordance with this invention, the loading and removing mechanism may easily be moved clear of the danger zone during firing, and as easily restored thereafter to its operative position. Part of the same mechanism may, additionally, serve as a base for various auxiliary operations such as may possibly be required.

In Figs. 2, 3 and 4, showing my improved arrangement, an excavating shovel 9 is suspended from a cable 9a the length of which is that necessary for the desired local control of the shovel 9. This cable 9a is suspended from a point 9b constituted by the connection between three converging cables 10, 11, 12 the upper ends of which are respectively wound over electrically-operated winches 14, 15, 13, which are in their turn suspended through corresponding rings from the service platform 6 so as to be capable of assuming any desired angular setting in space. The suspension points of the different winches are located at the outer circumference of the platform 6, angularly spaced by 120° from one another, as is clearly apparent from inspection of Fig. 4.

Obviously, it is possible to use more than three cables suspended from the periphery of the platform, for instance four cables, for the shifting of the excavating shovel laterally of the shaft; the surface over which the shovel may be shifted is then a square or rectangle the area of which is larger than that of the triangle defined by three cables. However, according to the investigations made, three cables should be sufficient in practice. The end in view is to position the shovel at any of various locations about the bottom of the shaft, so that it may pick up loosened material over the entire area thereof.

A workman located at 18 at the bottom of the pit operates, through a control box 17 provided with pusher knobs, the raising and lowering of the individual cables through different winches, either separately or simultaneously. The control cable 16 leading to the control box 17 may be wound over a drum 23 carried by the service platform, so as to be capable of increasing or decreasing in length as required by the workman at 18.

This workman may control the three winches in a manner such as to shift horizontally the excavating shovel 9 as desired within the outline of the triangle defined by the horizontal projections of the winches 13—14—15 and which encloses a sufficient area. Thus, it is possible to make the shovel take hold of all the

excavated material even outside said triangular area, because in such a case the shovel may be shifted by hand by the desired amount. The workman at 18 may alternatively control the winches from the platform 6, but when he is himself at the bottom of the pit, he controls more easily the work performed by the shovel. Lastly, the raising and lowering of the excavating shovel is obtained by acting simultaneously on the three winches 13, 14 and 15. In addition to the operator at 18, it is preferable to employ two men for guiding the hoisting buckets when they are lowered into their operative position and for engaging the hook onto the bucket to be raised. These two men are also entrusted with the work which consists in mounting on the bucket and removing therefrom a funnel-shaped collar 19 so as to further the emptying of the excavating shovel into it, and in guiding the latter so that it may take hold of the rock material even outside the triangular outline 13, 14, 15 as provided by a light shifting or traction exerted on the shovel 9 which carries handles for this purpose.

It should be remarked that the cables to which the excavating shovel is suspended are arranged in a manner such that, if the operator exercises reasonable care, they do not hinder the lowering and the raising of the hoisting buckets.

When the excavated material has been completely loaded in buckets, the excavating shovel 9 is raised into substantial contacting relationship with the service platform 6, as shown in Fig. 3. The control cable 16 is raised and laid on the platform 6, as provided preferably by its winding drum 23; the bottom of the shaft is now completely clear and the firing of the blasting charges may occur with practically no danger to any equipment, yet the removal of this equipment from and its restoration to operative position at the bottom of the shaft are extremely simple operations.

Fig. 5 shows a modification of the control means for the three cables 10, 11 and 12. According to this modification, the three electric winches disclosed hereinabove, for sake of simplification of the disclosure, may be replaced by a single winch 21 having three independent drums controlled by compressed air, for instance. Transmission pulleys 22 (Fig. 5) are then resorted to for obtaining the desired winding of the suitably distributed cables on the corresponding drums.

Such a winch may also be controlled from a distance either through an electric relay, or through compressed air or through a hydraulic control.

Turning now to the arrangement disclosed in Figs. 6 to 9, Fig. 6 shows again the excavated material 1 which is to be removed and the hoisting bucket 3 which, when filled, is hooked onto the cable 4 of the hoisting winch which raises it above ground, while a second cable 5 winds off the hoisting winch and lowers a further, empty bucket.

The excavating shovel 9 is connected with the three cables 10, 11, 12, the opposite ends of which are wound respectively over the electrically or pneumatically operated winches 13, 14, 15, which latter are each suspended through a ring to the service platform 6, which is suspended in its turn through the cable 7 and allows producing the annular concrete lining 8 of the pit.

In my improved arrangement, the usual mounting of the cables for opening or closing the excavating shovel is replaced by an arrangement including a cylinder 24 connected through a pivot pin 25 (Figs. 7 to 9) with the head 26 of the shovel. Inside the cylinder 24 may move a piston 27 the rod 28 of which is connected with the pivot 29 carrying the wall elements 30 of the excavating shovel so as to open the same when said pivot is lowered from the positions illustrated in Fig. 7 to that shown in Fig. 8. A protective casing 31 the lower end of which is connected with the spindle 29 is slidingly fitted over the cylinder 24, the lower end of said cylinder 24 communicates with a pipe 32 inside which flows com-

pressed air or the like fluid, the delivering of which is controlled by a valve 33.

A safety device constituted by a catch 34 is pivotally secured to one of the spindles 35 connecting the arms 36 of the excavating shovel with the head 26 (Fig. 9). The end 34a of the catch 34 is provided with a notch 37 cooperating with a projection 38 carried by the protective casing 31 while the other end 34b of the catch is submitted to the action of a spring 39 opposing the action of the rod 40 of a spring-urged piston 41 housed inside the casing 42 carried by the pipe 32 and fed thereby. Consequently, when compressed fluid is fed through the valve 33 into the pipe 42, the piston 41 is urged forwardly to urge the catch 34 against the action of the spring 39 into a position for which it releases said projection 38.

The operator 18 may stand on a control station 43 secured to the wall of the pit or suspended for instance from the winch 23, which latter is controlled from the actual station 43, which allows the operator at 18 to proceed with the operation of the excavating shovel 9 and of the valve 33 while watching the work from above.

When the operator at 18 is to load the hoisting buckets, he brings the excavating shovel into the desired location by coordinated lengthening or shortening of cables 10, 11, 12, after which, by closing the valve 33, he allows the compressed air to expand inside the cylinder 24 so as to make the piston 27, and thereby the casing 31, sink, which opens the excavating shovel as shown in Fig. 8. In order to close the shovel again, the operator 18 acts on the valve 33 so as to send again fluid under pressure into the pipe 32 whereby the piston 27 is urged upwardly again.

When the excavating shovel occupies its closed unlocked position, the cylinder 24 remains always under pressure and the safety catch occupies, in opposition to the spring 39, the position illustrated in dot and dash lines in Fig. 9. At the moment of the expansion of the compressed air or the like fluid, i. e. when the piston 27 begins its downward movement, the pressure inside the cylinder 24 diminishes speedily and the projection 38 carried by the casing 31 moves beyond the point of engagement with the end 34a of the catch, and prevents no longer, consequently, the complete opening of the shovel; the catch 34 occupies at this moment and by reason of the presence of the spring 39 the position illustrated in Fig. 8 and also in solid lines in Fig. 9.

In case of an untimely failure of the supply of fluid, and under the action of the spring 39, the end 34a of the catch snaps into engagement with the underside of the projection 38 so as to lock the casing 31 as illustrated in Fig. 7 and also in dotted lines in Fig. 9, which prevents any downward movement of the pivot 29 and consequently the opening of the shovel. As soon as the distribution of fluid becomes normal again, the pressure of the latter produces immediately, through the piston 41, the release of the catch 34 and the arrangement operates again as previously described. The control of such an excavating shovel may also be provided by a remote control through the agency of an electric relay for instance.

It should be remarked that an excavating shovel controlled by a choke damp-proof electric motor may be used, if allowed, in the same manner as any other excavating shovel controlled through a cable or a chain.

Obviously, it is possible to bring to the above embodiments that have been illustrated in accompanying drawings, various modifications in shape and also in the mounting, design and arrangement of their component

parts, without unduly widening thereby the scope of the invention as defined in the accompanying claims.

What I claim is:

1. An apparatus for sinking vertical mine shafts, comprising a service platform of appreciable width and length, having an area with shape approximating the cross-sectional area and shape of the shaft, and having two holes through it, a pair of hoisting buckets for receiving loosened material, means supporting said platform at a safe distance above the bottom of the shaft, means above said platform suspending said buckets in alignment with the respective holes in the platform, for lowering the same alternately to the bottom of the shaft and raising the same through their respective holes to a higher discharge point, an excavating shovel, power means carried thereby to open or to close the same, several suspension devices carried by the service platform and arranged thereon in a polygonal pattern, adjacent its perimeter, flexible suspension cables extending from said suspension devices and converging to said excavating shovel, means for winding in or out each suspension cable, through the locations of said several suspension devices, conjointly with or independently of the winding in or out of any or all other such cables, control means distant from the excavating shovel, and operatively connected to the winding means to control the winding in or out of each cable by such winding means, and control means distant from said excavating shovel for controlling the power means for opening and closing the same.
2. An apparatus for sinking mine shafts as defined in claim 1, wherein said supporting members arranged on the perimeter of said service platform for supporting the upper ends of the excavating shovel supporting cables are constituted by winches which also serve as the winding means for said cables.
3. An apparatus for sinking mine shafts as defined in claim 1, wherein said supporting members arranged on the perimeter of said service platform for supporting the upper ends of the excavating shovel supporting cables are constituted by idle pulleys, and said winding means are constituted by a single winch having individual drums for each such cable, adapted to be independently driven for winding and unwinding said cables respectively.
4. An apparatus for sinking mine shafts as defined in claim 1, wherein said control means are supported from said service platform.
5. An apparatus for sinking mine shafts as defined in claim 4, including a control line hanging from said service platform, and a winch upon said platform for reeling in said control line, the control means being carried at the lower end of said control line.
